UNITED STATES PATENT OFFICE.

ALFRED H. DYSON, OF MONTCLAIR, NEW JERSEY, ASSIGNOR, BY MESNE ASSIGNMENTS,
TO WESTERN ELECTRIC COMPANY, INCORPORATED, A CORPORATION OF NEW YORK.

AUTOMATIC TELEPHONE SWITCHING SYSTEM.

1,207,150.

Specification of Letters Patent.

Patented Dec. 5, 1916.

Application filed March 8, 1915. Serial No. 12,810.

To all whom it may concern:

Be it known that I, ALFRED H. DYSON, a citizen of the United States, residing at Montclair, in the county of Essex and State of New Jersey, have invented certain new and useful Improvements in Automatic Telephone Switching Systems, of which the following is a full, clear, concise, and exact description.

10 This invention relates to controlling circuits for switching apparatus used in automatic telephone systems.

One of the objects of this invention is the provision in a system in which the subscribers' lines are divided into a plurality of groups, of means whereby a series of relays definitely associated with the lines of said groups will be employed to select that group of contacts in which a calling line 20 terminates.

Another feature of the invention resides in the provision of circuits for controlling the operating mechanism which is common to a plurality of switches.

25 In the drawings—Figure 1 shows a plurality of subscribers' lines, each being in a different group, and the group selecting relays associated therewith; in Fig. 2 a selector switch and the common actuating mechanism are diagrammatically illustrated together with the controlling circuits therefor; Fig. 3 is a view showing one of the endless worms and the supporting frame for the magnets mounted thereon.

30 The switch structure herein shown aside from the operating mechanism, may be substantially such as described in Patent No. 1,123,696 and will therefore be only briefly described herein.

35 The switch comprises a longitudinally movable shaft 1 having a plurality of sets 2 of brushes fixed thereto. These sets of brushes will ordinarily be five in number, but only two are shown in the drawing.

40 Each set 2 of brushes is arranged to traverse a section 3 of the line terminals. Rotatable power drums 4 and 5 are provided and when the elevating bar 6 of the switch is forced into engagement therewith by means of one 45 of the idler pulleys 7 or 8 respectively, cause the brush shaft to be driven upwardly to its set position or downward to normal as the case may be.

Carried by the shaft 1 are a plurality of interrupter brushes 9, 10 and 11, which in the movement of the switch shaft, are caused to traverse their respective commutators or interrupters (shown in Fig. 2) to control the operation of the switch mechanism, as will later appear.

55 The brushes of each of the sets 2 are normally held in a position so they will not engage the line terminal contacts by means of a controlling member 12 positioned between the two innermost brushes of the set.

60 A rotatable trip rod 13 is mounted parallel to the shaft 1. This rod is provided adjacent each controlling member with a co-operating member by means of which the brushes may be released. These co-operating members are positioned at progressively increasing distances from the normal position of the controlling members 12.

65 If the rod 13 is rotated during the preliminary upward movement of the switch shaft, one of its co-operating members will engage a corresponding controlling member 12 to release a set of brushes. Thus it will be seen that the set of brushes to be tripped or released depends on the distance the shaft 70 travels prior to the rotation of the trip rod 13.

75 The common actuating mechanism which is diagrammatically illustrated in Fig. 2 of the drawings, is designed for use with any 80 one of a plurality or group of selectors. Heretofore switches of the type herein disclosed have required a set of operating magnets individual to each switch. By this invention the individual operating mechanisms 85 are dispensed with and a single set of operating magnets and associated parts are provided to control the operation of a group of switches. The magnets which control the upward movement of the switch carriage and the tripping of the desired set of brushes are mounted in one frame, and the release and down-drive magnet is mounted in a 90 separate frame. By means of endless worms the frames are shifted into position so that 95 the magnets carried thereby may control the operation of any desired switch either to cause it to move upward to its set position or to release it and return it to normal, as the case may require. As the operation 100 of this mechanism will be readily under-

stood from the following description of the circuits and as the details thereof form no part of the present invention, this mechanism will be only briefly described. However, a more complete description of this device will be found in patent issued to James L. McQuarrie, No. 1,204,486, patented November 14, 1916.

The idler pulleys 7 and 8, carried by the common actuating mechanism are adapted to force any one of the elevating bars 6 into engagement with the power shafts 4 and 5, respectively.

The up-drive power drum 4 is provided at the end thereof with a friction disk 15. Extending parallel to the drum 4 but on the opposite side of the elevating bars 6 is a shaft 16 provided with an endless spiral groove 17. (See Fig. 3). Mounted on the endless worm 16 is a frame 18 indicated by dotted lines in Fig. 2, carrying a follower 19 seated in the endless groove 17. The shaft 16 with the spiral groove thereon will hereinafter be referred to as an endless worm. This worm is provided at one end, adjacent the friction drum 15, with a friction wheel 20. Secured to the end of the armature 21 of the electromagnet 22 is a link 23, to the outer end of which is rotatably secured a friction roller 24. Upon energization of the magnet 21 this roller is caused to operatively engage the power disks 15 and 20 and transmit a rotary motion from disk 15 to disk 20. The up-drive clutch magnet 24 and its armature 25 are mounted in the frame 18. The idler pulley 7 is secured to the armature 25 in such a manner that upon energization of the magnet 24 the pulley will engage an elevating bar 6 and force it into operative engagement with the power drum 4. Also carried by the frame 18 is a brush selecting or tripping magnet 26. Pivotally mounted on the frame below the lowermost set of brushes and individual to each trip rod 13 is a link 14 which is secured to a projecting portion of the trip rod by a strap 14'. If, when the common actuating mechanism is in position before any switch bar 6, the trip magnet 26 is energized, its armature 27 will engage the link 14 and cause the rotation of the trip rod 13.

The endless worm 28 is mounted parallel to the down-drive drum 5, but on the opposite side of the elevating bars. The down-drive drum 5 and the worm 28 are provided with friction disks 29 and 30 respectively, the operative relation of which is caused by the friction roller 31 carried by the armature of the electromagnet 32. Mounted on the frame adjacent to the down-drive drum 5 are the holding pawls 33, one for each switch. These pawls are adapted to engage the perforations 35 in the bars 6 and maintain the switch shafts in their elevated po-

sitions. The frame 36, which is mounted on the lower endless worm 28, carries the electromagnet 37 which has the two-fold purpose of retracting the holding pawls 33 and of forcing the bar 6 into engagement with the down-drive drum. This magnet 37 is provided with an armature 38, to the upwardly extending portion of which is secured the idler pulley 8 and a finger 40, adapted upon energization of said magnet to engage the downwardly extending end of a pawl 33 and cause it to disengage its bar 6.

The brushes 51, 52, 53, 54, 55 and 56 are carried by the upper frame 18, and in the movement of the upper common actuating mechanism from switch to switch, are arranged to traverse the contacts in the bank 57.

The brushes 58, 59, 60 and 61 are carried by the lower frame 36 and in the movement of the common release mechanism from switch to switch these brushes will traverse the contacts in the bank 62.

A set of the contacts in each of banks 57 and 62 are provided before each elevating bar 6.

In the circuits shown in Figs. 1 and 2, the above described device is used as a line finder. This switch, as previously described, is a multiple brush structure. In practice five sets of brushes are usually provided, each adapted to traverse a section of the fixed terminals in the panel bank. Each section in the bank may be provided with as many fixed terminals as desired, one hundred being a common number, but in a line finder a smaller number may be employed. Each section of the contacts on the panel represents multiple terminals of a group of subscribers' lines.

Referring to Fig. 1, the subscriber's station shown at the right represents one of the 0 group of subscribers whose lines terminate on the lowermost section of the panel. The subscriber's station next to the left represents one of the subscribers in the 1 group which subscribers' lines terminate at the second section from the bottom of the panel bank. The middle subscriber's station is connected to terminals on the middle section of the contact bank and so on. While only two groups or sections of contacts are indicated in Fig. 2, it is to be understood that in the embodiment of the invention herein disclosed there will be five groups of line terminals. A pair of relays 65 and 66 which may be termed counting relays will be provided for each group of lines. That is, for each group of subscribers' lines there will be a pair of relays 65 and 66 common to all the lines of the group. Associated with the five pairs of relays of the said groups is a double wound relay 67 and a relay 68. These relays being common

to all the lines which terminate in the fixed contacts of a finder switch or group of finder switches.

A sequence switch such as those which serve to control the circuits herein shown is fully described in Patent No. 1,127,808. It may be noted that in the specification the numeral in brackets which follows a reference character used to designate a sequence switch contact, indicates the position of the sequence switch, at the time the circuit being traced is completed. On the drawings the numeral or numerals adjacent to a sequence switch contact indicates the position or positions in which the contact is closed, except the controlling contact A which is open only at the positions indicated.

Assuming now that the subscriber at substation S (Fig. 1), initiates a call by removing his receiver from the hook, a circuit will be completed from grounded battery through line relay 69, contact of cut-off relay 70, the substation apparatus and back to ground through the left armature of cut-off relay 70. Relay 69 will be energized and complete a circuit from ground through its armature and inner contact, conductor 71, armature and back contact of relay 65', conductor 72, sequence switch contact J (2), conductor 73 and left winding of relay 74 to grounded battery.

Before continuing the description, it may be noted that the finder switch next to be used in finding a calling line is preselected and that the common operating mechanism is in association therewith. It should also be noted that the sequence switch of this pre-selected line finder stands in position 2. The manner in which this is accomplished will hereinafter appear.

When relay 74 is operated it completes a circuit from ground through its right armature and front contact, sequence switch contact B (2); conductor 75, sequence switch motor magnet 76 to battery and ground. The sequence switch then moves from position 2 to position 3. This interrupts the energizing circuit for relay 74 which falls back, completing through its right armature a circuit from ground, sequence switch contact B (3) and sequence switch motor magnet 76 to battery and ground. This moves the sequence switch to position 4. In position 4 a circuit is completed from grounded battery through the left winding of relay 74, sequence switch contact J (4) conductor 77, relay 68, back contact of relay 67, conductor 78, sequence switch contact G (4) to ground. (Conductors 72, 77 and 78 are multiplied to correspond to sequence switch contacts of all the line finders of a group). Relays 74 and 68 are energized.

Relay 68 completes a circuit from battery through relay 66, back contact of relay 65 to ground. Relay 66 pulls up and completes

a circuit for itself in series with relay 65 through conductor 78 to ground at contact G (4). Relay 65 does not pull up, however, due to its being short circuited by the armature of relay 68.

Relay 74 completes through its right armature and sequence switch contact B (4) a circuit for sequence switch motor magnet 76 and the sequence switch goes to position 5. In position 5 a locking circuit is established for relays 74 and 68, which extends from grounded battery through the left winding of relay 74, front contact and left armature of said relay, sequence switch contact J (5), conductor 77, winding of relay 68, back contact of relay 67, conductor 78, sequence switch contact G (5) to ground.

Under the assumption that the common actuating mechanism is associated with the set of contacts in the bank 57, which are individual to the preselected switch to be operated in position 5 of the sequence switch, a circuit will extend from grounded battery through conducting strip 79, brush 51, the up-drive clutch magnet 24, brush 55, sequence switch contact C (5) and front contact and right armature of relay 74 to ground. The clutch magnet is energized and the brush shaft moves upward.

Just prior to reaching the first brush selecting position the interrupter brush 10 engages the lowermost conducting segment of the interrupter 80. This causes the relay 68 (Fig. 1) to be shunted by a circuit extending from ground, through said interrupter brush and the interrupter, sequence switch contact H (5) to sequence switch contact J (5), where it joins the series circuit through the left winding of relay 74 and relay 68. The deenergization of relay 68 removes the short circuit from relay 65. Relay 65 is energized and in pulling up opens the shunt circuit extending to the armature of relay 68 and completes through its left front contact a circuit to relay 66', whereby it will be energized upon the next operation of relay 68.

When the switch reaches the first brush tripping position the interrupter brush 10 engages an insulated segment of the interrupter. Relay 68 again attracts its armature and completes a circuit from ground, through the inner left contact of relay 65, back contact of relay 65' to battery, through counting relay 66'. Relay 66' attracts its armature and completes a locking circuit for itself in series with relay 65', which circuit extends through its contact and armature and over conductor 78 to ground through sequence switch contact G (5), as before, Relay 65' being short circuited does not pull up until relay 68 deenergizes when the interrupter brush 10 engages the second conducting segment of the interrupter 80, which occurs the next instant.

As we assumed that subscriber at substation S has removed his receiver from the hook and that line relay 69 is in its energized condition, upon the energization of 5 relay 65' a circuit will be completed from ground, through armature and front contact of relay 69, conductor 71, armature and front contact of relay 63', and left winding of relay 67, to grounded battery. The conductor 71 and similar conductors at the other groups are each multiplied to the front contacts of all the line relays in their respective groups. Relay 67 is energized and 10 interrupts the series holding circuit through left winding of relay 74 and relay 68. Now, when the switch reaches the second brush selecting position, the interrupter brush 10 moves on to the next insulating segment of 15 interrupter 80. This interrupts the other 20 branch of the holding circuit of relay 74 which falls off and completes through sequence switch contact B (5) a circuit for sequence switch motor magnet 76, and the sequence switch moves to position 6. In position 25 a circuit for the trip magnet 26 is completed from battery, through conducting strip 79, brush 51, winding of magnet 24, brush 54 and the contact engaged thereby to ground through sequence switch contact D (6).

It will now be clear that due to the operation of interrupter 80 and brush 10 successive pairs of relays 65, 66 will be energized and locked up as the switch passes 30 through the corresponding brush selecting positions. When the relay 65 associated with the group of a calling line pulls up, it causes the cutoff relay 67 to operate and interrupt one branch of the holding circuit of 35 relay 74. Now when the brush 10 passes on to the next insulating segment the other branch of the holding circuit for relay 74 is interrupted, the relay falls off and drives the sequence switch to brush tripping position 40.

The magnet 26 attracts its armature which engages the end of link 14, causing it to rock outwardly, and through the medium of strap 14' to rotate the trip rod 13. This 45 causes the release of the second brush set from the bottom. Had the calling substation been in another group as the 2 group, the lines of which terminate on third from the bottom section of the panel bank, the middle brush set would have released.

In position 6 a circuit is completed from 50 grounded battery through the left winding of relay 74, to ground, through sequence switch contact G (6). Relay 74 through its 55 right armature and contact B (6) completes a circuit for motor magnet 76 which moves the switch into position 7.

In position 7, the previously traced circuit for up-drive clutch magnet 24 is again 60 completed, and the shaft 1 moves upwardly 65

causing the brushes thereof to traverse the line terminal contacts of its respective section of the panel bank. During the travel of the switch from its brush tripping position until the brushes engage the first set of 70 contacts in the bank a holding circuit is provided from battery through left winding of relay 74, contact and left armature of said relay contact E (6 to 7), conducting segment 81, to ground through brush 9. 75

In position 7, a test circuit is provided from grounded battery, through the left winding of relay 74, its left contact and armature, sequence switch contact H (7), the left brush of the switch to the contact 80 engaged thereby. Unless the line which terminates at a set of contacts engaged by the brush is a seeking line, the contact engaged by the left brush will be grounded. If the line is idle, the guarding potential will be 85 supplied through the back contact of the line relay of the respective line, and if the line is busy, through the test brush in engagement with one of its multiple contacts, to ground through sequence switch contact 90 H of said switch, as will presently appear. Relay 74 is therefore maintained energized until the switch brushes engage the contacts of the calling line. Ground potential will not be found upon the test contact of a calling line as the line relay will be energized. Therefore when the switch reaches the terminals of a calling line relay 74 will be de-energized, interrupting the circuit of the clutch magnet 24 and completing at its back 95 contact and right armature a circuit through sequence switch contact B (7) and sequence switch motor magnet 76 to grounded battery. The sequence switch then moves into position 8. 100

Should the calling subscriber replace his receiver on the hook before the brushes have reached the terminals of his line, or for any other reason, should the test of the calling line fail to take place, the switch shaft will 105 continue to be moved upwardly until the brush 11 engages the conducting segment 82, when a circuit will be completed through sequence switch contact K (7) for the motor magnet 76, which will move the sequence switch into position 8. In position 110 8 the power circuit will be interrupted at contact C and a circuit will be completed from grounded battery, tell tale signal contact K (8), segment 82 and brush 11 to ground. The operation of signal 82 will indicate the position of the switch to an observer who can then determine the cause of trouble. If, sequence contact K is arranged 115 to be closed in positions 1 to 9 instead of 1 to 7 the signal will receive only a flash and the sequence switch will be carried directly to position 18 which as will hereinafter appear, is the return to normal position. 120

Returning now to the point where the 125

switch has stopped on the contacts of the calling line, in position 8 a circuit is completed from ground, through sequence switch contact F (8) to battery through the signal light 83, associated with the jack at the outgoing end of the trunk which terminates in the actuated line finder. While a plug and jack switch is shown at the outgoing end of this trunk, it is to be understood that any other form of a line connecting device may be equally as well employed. The sequence switch remains in position 8 until the plug 84 is inserted in jack 85, when a circuit is completed from ground, 15 through the right winding of relay 74, sleeve contacts of the plug and jack, to grounded battery. Relay 74 is energized and completes through its front contact and contact B (8) an energizing circuit for sequence switch motor magnet 76, which moves the sequence switch into position 9. In position 9 the talking strands of the 20 trunk are completed from the line finder brushes to the jack by means of the sequence switch contacts E and F (9).

At the time the sequence switch passed into position 8, a circuit was completed from grounded battery through the winding of clutch magnet relay 86, brush 53, the contact 30 engaged thereby to ground, through sequence switch contact D (8 to 18) to ground. Relay 86 is energized and completes a circuit from ground, through its armature and front contact, clutch magnet 21 to grounded 35 battery. Magnet 21 is energized and by attracting its armature operatively engages the friction disk 24 with the power disk 15 and the friction disk 20 at the end of the worm 16. This causes the common up drive 40 mechanism to move out of association with the finder switch just actuated.

The sequence switch of any selector which is at this time in use will be in either position 1, if the switch is in its normal position, or will be in position 18 if it is awaiting return to normal. No sequence switch, 45 except the one with which the common mechanism is associated, can be in positions 2 to 8.

50 As the worm 16 rotates, it moves the common mechanism away from association with the switch just actuated and into association with the next switch, its circuit controlling brushes 51 to 56 being caused to engage the next set of contacts in the bank 57. This may be the next set, either at the right or at the left, depending upon in which half of the spiral the follower 19 is located.

60 We will now assume that the next finder switch is an idle one, in which case the sequence switch thereof will be in position 1 and sequence switch contact D will be open. Relay 86 will be maintained energized until the brushes are centrally positioned on the 65 next set of contacts in the bank 57 by means

of the engagement of brush 52 with one of the grounded contacts 87. When, however, the common mechanism is centrally positioned before the idle switch the circuit of relay 86 will be interrupted. Relay 86 in 70 retracting its armature will open the circuit for clutch magnet 21, stopping the actuating mechanism in association with this switch. Relay 86 in retracting its armature will also complete a circuit from 75 grounded battery, through the sequence switch motor magnet (corresponding to 76) of the selector switch with which the common mechanism is now associated. This circuit may be traced from battery through 80 said motor magnet, sequence switch contact B (1), contact and brush 56 of the common mechanism to ground through the back contact and armature of relay 86. The sequence switch of the selected line finder 85 will then move into position 2, in which position we find it when the next call is initiated by a subscriber.

Now we will assume that the next switch with which the common actuating mechanism is associated is busy or is awaiting return to normal. In either case contact D (8 to 18) will be closed and relay 86 will be maintained energized by a circuit through brush 53 and said contact; thus causing the 90 mechanism to move on to the next switch. Thus it will be seen that the common mechanism will stop in association only with a switch which is idle and is in its normal position. At the end of conversation the 100 operator will remove the plug from the jack.

The sequence switch at this time will be in position 9 or in talking position. The removal of the plug interrupts the holding circuit through the right winding of relay 105 74 and the retraction of its right armature completes a circuit through contact B (9) for sequence switch motor magnet 76, which causes it to move from position 9 directly to position 18 or return to normal position. 110

In position 18 sequence switch contact L is closed. This grounds the common conductor 92. The common return to normal mechanism, except when in active service, will be associated with a line finder, the 115 sequence switch of which is in positions 1 to 17. That is, it will never remain inactive in association with a switch, the sequence switch of which is in position 18 which is the return to normal position. 120

Assuming that the common mechanism is now associated with the switch corresponding to the sequence switch having contact L'. The sequence switch of this switch will be somewhere from positions 1 to 17, and a 125 circuit will be completed from ground through sequence switch contact L' (18), common conductor 92, sequence switch contact L' (1 to 17), test contact and brush 60 in engagement therewith, clutch magnet re- 130

lay 88, to grounded battery. Relay 88 will operate and complete a circuit for magnet 32, which in pulling up will force the friction disk 31 into operative engagement with the power drum 29, and the friction disk 30 at the end of worm 28. The worm 28 will revolve, causing the common return mechanism to be shifted from switch to switch. Ground potential will be maintained upon the common return mechanism test contacts of all switches, except the one awaiting return to normal. This ground potential will be supplied through contacts L', L'', etc., of the several switches. Magnet 32 will be maintained energized, and the worm 28 will continue to rotate until the brush 60 engages the contact in bank 62 connected to sequence switch contact L of the finder awaiting return to normal which will be open. When the mechanism has been centrally positioned before this switch, brush 59 will disengage the centering segment 87 and relay 88 will fall off and open the circuit of magnet 32 to stop the mechanism in association with the desired line finder. The sequence switch of this line finder being in position 18, a circuit will be completed from ground, through sequence switch contact D (18), contact and brush 61, back contact of relay 88, release and down-drive magnet 37, through the upper brush 58 and conducting segment engaged thereby to grounded battery. The holding pawl 33 will be retracted and the switch will be lowered by the action of the drum 5 on the bar 6. As the switch approaches its lowermost position, the interrupter brush 11 will engage the conducting segment 90, completing a circuit through sequence switch B (18) for the sequence switch motor magnet 76, which will drive it from position 18 to position 1. It is now in a position to be again selected by the common up-drive mechanism.

What is claimed is:

- 45 1. In a telephone system, telephone lines divided into groups, a series of relays, one being common to all the lines of each group, an automatic switch, means automatically actuated incident to taking one of said lines for use for causing the movement of said switch, positions for said switch corresponding to said line groups, means for actuating one of said relays as said switch moves to each group position, and means for arresting the movement of said switch when the relay associated with the group of the selected line is actuated.
- 60 2. In a telephone system, telephone lines having terminals divided into groups, a series of relays, one being common to all the lines of each group, an automatic switch, means automatically actuated incident to taking one of said lines for use for causing the movement of said switch, group selecting positions for said switch corresponding to

said line groups respectively, means for actuating one of said relays as said switch moves to each group selecting position, and means for operatively associating said switch with the terminals of the group of 70 the line taken when the relay corresponding to said group is actuated.

3. In a telephone system, telephone lines having terminals divided into groups, a series of pairs of relays, a pair being common to the lines of each group, an automatic switch, means automatically actuated when one of said lines is taken for use for causing the movement of said switch, positions for said switch corresponding to said line groups respectively, means for actuating a pair of said relays as said switch moves to each position, and means for operatively associating said switch with the terminals of the group of the line taken when 85 the last relay of the pair corresponding to said group is actuated.

4. In a telephone system, telephone lines having terminals divided into groups, pairs of counting relays, a pair being common to 90 the lines of each group, an automatic switch, means automatically actuated when one of said lines is taken for use for causing the movement of said switch, normally inoperative multiple brushes on said switch, one 95 for each group of terminals, brush selecting positions for said switch corresponding to said groups of terminals respectively, means for energizing and locking up a pair of said relays as said switch moves to each brush 100 selecting position, and means for operatively associating a brush with the terminals of the group of the line taken when the pair of relays corresponding to said group is actuated.

5. In a telephone system, subscribers' lines divided into groups, a series of relays, one being common to all the lines of each group, an automatic switch, means for causing the movement of said switch upon the initiation 110 of a call on any of said lines, positions for said switch corresponding to said line groups, means for actuating one of said relays as said switch moves to each group position, and means for arresting the movement of said switch when the relay associated with the group of a calling line is actuated.

6. In a telephone system, subscribers' lines having terminals divided into groups, 120 a series of relays, one being common to all lines of each group, an automatic switch, means automatically actuated upon the initiation of a call on one of said lines for causing the movement of said switch, group selecting positions for said switch corresponding to said line groups respectively, means for actuating one of said relays as said switch moves to each group selecting 125 position, and means for operatively associating

ating said switch with the terminals of the group of the calling line when the relay corresponding to said group is actuated.

7. In a telephone system, subscribers' lines having terminals divided into groups, a series of relays, one being common to all the lines of each group, an automatic switch, means automatically operated upon the initiation of a call on one of said lines for causing the movement of said switch, group selecting positions for said switch corresponding to said line groups respectively, means for actuating one of said relays as said switch moves to each group of said selector positions, and means for operatively associating said switch with the terminals of the group of the calling line when the relay corresponding to said group is actuated.

20 8. In a telephone system, subscribers' lines having terminals divided into groups, a series of pairs of relays, a pair being common to the lines of each group, an automatic switch, means automatically actuated upon the initiation of a call on one of said lines for causing the movement of said switch, positions for said switch corresponding to said line groups respectively, means for actuating a pair of said relays as said switch moves to each position, and means for operatively associating said switch with the terminals of the group of the calling line when the last relay of the pair corresponding to said group is actuated.

35 9. In a telephone system, subscribers' lines having terminals divided into groups, a series of counting relays, one being common to the lines of each group, an automatic switch, means automatically actuated upon the initiation of a call on one of said lines for causing the movement of said switch, positions for said switch corresponding to said line groups respectively, means for energizing and locking up one of said relays as said switch moves to each position, and means for operatively associating said switch with the terminals of the group of the calling line when the relay corresponding to said group is actuated.

50 10. In a telephone system, subscribers' lines having terminals divided into groups, a series of relays, one being common to the lines of each group, an automatic switch, means automatically actuated upon the initiation of a call on one of said lines for causing the movement of said switch, group selecting positions for said switch corresponding to said groups of lines respectively, means for energizing and locking up one of said relays as said switch moves to each selecting position, and means for operatively associating said switch with the terminals of the group of the calling line when the relay corresponding to said group is actuated.

65 11. In a telephone system, subscribers'

lines having terminals divided into groups, a series of relays, one being common to the lines of each group, an automatic switch, means automatically actuated incident to the initiation of a call on one of said lines for causing the movement of said switch, brushes on said switch one for each group of terminals, brush selecting positions for said switch corresponding to said groups of lines respectively, means for actuating one of said relays as said switch moves to each brush selecting position, and means for operatively associating a brush with the terminals of the group of the calling line when the relay corresponding to said group is actuated.

12. In a telephone system, subscribers' lines having terminals divided into groups, pairs of counting relays, a pair being common to the lines of each group, an automatic switch, means automatically actuated incident to the initiation of a call on one of said lines for causing the movement of said switch, normally inoperative multiple brushes on said switch, one for each group of terminals, brush selecting positions for said switch corresponding to said groups of terminals respectively, means for energizing and locking up a pair of said relays as said switch moves to each brush selecting position, and means for operatively associating a brush with the terminals of the group of the calling line when the pair of relays corresponding to said group is actuated.

13. In a telephone system, subscribers' lines having terminals divided into groups, relays common to the lines of each group, an automatic switch, means automatically actuated incident to the initiation of a call on one of said lines for causing the movement of said switch, group selecting positions for said switch corresponding to said groups of lines respectively, means for energizing and locking up one of said relays as said switch moves to each group selecting position, and means for operatively associating said switch with the terminals of the group of the calling line when the last relay of the pair corresponding to said group is actuated.

14. In a telephone system, subscribers' lines having terminals divided into groups, pairs of counting relays, a pair being common to the lines of each group, an automatic switch, means automatically actuated incident to the initiation of a call on one of said lines for causing the movement of said switch, normally retracted multiple brushes on said switch, one for each group of terminals, brush selecting positions for said switch corresponding to said brushes respectively, means for energizing and locking up a pair of said relays as said switch moves to each brush selecting position, and means for releasing the brush having access to the terminals of the group of the calling

line when the last relay of a pair corresponding to said group is actuated.

15. In a telephone system, a group of switches, common mechanism for controlling the movement of said switches, an electro-magnet for operating said mechanism, a circuit for operating said electro-magnet, means for closing said circuit automatically actuated when said mechanism has finished its operation with one of said switches for causing it to move to and be operatively associated with the next idle switch of said group and means for opening said circuit when said mechanism is associated with said idle switch.

16. In a telephone system, a group of switches, common mechanism for controlling the movement of said switches to their operative positions, an electro-magnet for operating said mechanism, a circuit for operating said electro-magnet, means for closing said circuit automatically actuated when said mechanism has finished its operation with one of said switches for causing it to move to and be operatively associated with the next idle switch of said group and means for opening said circuit when said mechanism is associated with said idle switch.

17. In a telephone exchange system, a group of switches, common mechanism for governing the return to normal of said switches, an electro-magnet for operating said mechanism, a circuit for said electro-magnet, means for controlling said circuit, and means to automatically actuate said circuit controlling means upon breaking the connection through an actuated switch for associating said common mechanism therewith to return said switch to its normal position.

18. In a telephone exchange system, a group of lines, a plurality of switches, any one of which may operatively engage any of said lines, common operating mechanism

for said switches, means actuated upon the initiation of a call on any one of said lines for causing a selected switch to move to and associate itself with the terminals of said line, an electro-magnet for operating said mechanism to move it to the next idle switch of said group, a circuit for said electro-magnet, means to close said circuit when said circuit switch has been associated with the terminals of said line, and means to open said circuit when said mechanism has been associated with the said next idle switch.

19. In a telephone exchange system, a plurality of subscribers' lines divided into groups, groups of terminals corresponding to said groups of lines respectively, a plurality of switches, normally inoperative multiple brushes on each of said switches, one being adapted to traverse each of said groups of terminals, a common operating mechanism for said switches, means automatically actuated upon the initiation of a call on one of said lines for causing the release of the brush having access to the group of the calling line and for causing the movement of said brush to the terminals of said line, and means thereupon automatically actuated for causing said common mechanism to be associated with the next idle switch of the group, said last named means comprising an electro-magnet for operating said mechanism, and a circuit for said electro-magnet closed on association of the circuit switch with the terminal of said line, and opened when said mechanism has moved to said next idle switch.

In witness whereof, I hereunto subscribe my name this sixth day of March, A. D. 1915.

ALFRED H. DYSON.
